SAFETY BELT

Filed April 18, 1927

Inventor:

Charles F. Jacobs
By James Addington, Ames & Ichbold
Attnys.

UNITED STATES PATENT OFFICE.

CHARLES E. JACOBS, OF VALPARAISO, INDIANA.

SAFETY BELT.

Application filed April 18, 1927. Serial No. 184,586.

My invention relates to safety belts for use by linemen working on telephone poles, aerial structures, and the like.

An object of the invention is to provide a safety belt or strap for holding the lineman on the pole in the event of an accident, thereby preventing him from losing his balance and dropping to the ground.

At the present time, a tool belt is provided 10 to encircle the body of the lineman and a safety strap is then adapted to be buckled thereto, which may extend about the pole to allow the lineman to lean outwardly, with his feet spurred into the pole to balance 15 himself. In this position, the lineman may perform such repairs as are required on the pole, but his connection must allow freedom to permit him to reach outwardly to work on wires and cross-beams attached to the 20 pole. Such freedom should allow working at a distance from the pole so as to move with safety about the wires without danger of being electrocuted. Quite often, however, linemen will come into contact with exposed 25 line wires of high voltages and the shock will be sufficient to render them unconscious, thereby causing their feet to be released from against the pole and their balance or support lost. The result is that their weight 30 on the strap is relaxed and this strap then loosely encircles the pole and allows the lineman to drop. It has been found that such a drop is more apt to kill the lineman 35 while unconscious. Records show that a relatively large number of men are seriously 40 injured or killed each year by dropping to the ground, as the result of losing their balance, either by coming into contact with exposed high voltage lines or by other mis- 45 haps, and by the safety strap breaking.

One of the principal objects of my invention is the provision of an auxiliary securing means adapted to secure the safety strap to the pole so that in the event the lineman 45 loses his balance by contact with live wires or by his feet slipping, it is impossible for him to drop.

More specifically, my invention provides 50 an auxiliary securing means in the form of a strap attached to, or otherwise carried by the safety strap, and of a size capable of being strapped about the pole so as to prevent the safety strap from being carried downwardly along the pole in the event the weight

of the lineman on the strap is relaxed and 55 resultant frictional binding engagement of the strap about this pole is released.

A further object of my invention is to provide an auxiliary safety strap of the above type, which will hold the lineman to the pole, 60 in the event the safety strap, which encircles the pole, should fail by breaking or its snaps unbuckling.

A still further object of my invention resides in attaching the auxiliary strap to the 65 safety strap, in adjustable relation, whereby the linemen will have a certain latitude of movement while held thereby.

Other objects and advantages of my invention will be apparent from the detailed specification and accompanying drawings forming a part hereof in which:

Figure 1 is a perspective view of a lineman supporting himself on a pole;

Fig. 2 is a plan view of a safety strap 75 embodying my invention;

Fig. 3 is a detailed view of a portion thereof illustrating a modified form of my invention;

Fig. 4 is a vertical sectional view taken 80 on line 4-4 of Figure 3;

Fig. 5 is another modified form of my invention;

Fig. 6 is a further modified form of my invention; and

Fig. 7 also shows a modified form of my invention.

While I shall describe several alternative forms of my invention, it will be remembered that I do not intend to limit myself to any 90 specific construction inasmuch as the invention relates broadly to the provision of an auxiliary safety device adapted to be used in conjunction with a lineman's safety strap for holding the strap secured to the pole to 95 prevent the lineman from dropping in the event of an accident.

In the drawings it will be observed that the usual body belt 5 is provided to encircle the lineman about the waist, this belt having 100 loops 6 securely attached thereto at its ends and the end portions 7 and 8 furnished with an adjustable buckle 9 permitting attachment of belt 5 to the body.

In connection with belt 5 there is provided 105 a safety strap 10 adapted to encircle the pole, as illustrated in Fig. 1, and connected to the ends of belt 5 by snaps 11 adapted to be

hooked into buckles 6. Safety strap 10 is also adjustable at 12 to vary the distance the lineman may lean outwardly from the pole 14.

5 My invention contemplates providing an auxiliary safety strap 15 attached to the strap 10 intermediate its ends, as illustrated in Figure 2, and of a length permitting it to encircle the pole and to be fastened by means 10 of a buckle 16. It will be observed that the end 17 of strap 15 is furnished with a plurality of openings 18 to permit attachment of the belt whereby to encircle poles of various diameters.

15 It is also customary for these poles to taper from the bottom to the top, and consequently, it is highly desirable that this strap 15 be adjustable, so that it may be attached at any point along the pole.

20 Those skilled in the art are aware of the fact that linemen are provided with spurs 20 which are strapped to their legs and extending outwardly from their feet to permit spurring into the pole. By means of 25 these spurs 20, a lineman is able to lean outwardly from the pole against the strap 10, so as to be in a position to make repairs or otherwise work on the line, as illustrated in Figure 1.

30 It is by the balancing effect that is obtained by the feet being secured to the pole and the strap encircling the same that the lineman is able to obtain his balance while working. It is apparent, however, that in 35 the event of receiving a shock from high voltage wires, to which he is constantly exposed, his body will relax and his feet be freed from the pole whereby, if the safety strap 15 were not provided, the strap 10 would allow him to drop to the ground. By 40 the provision of the auxiliary safety strap 15 it is impossible for the lineman to drop in the event of an accident of this kind. On the other hand, there is danger of the snaps 45 11 giving way or the strap 10 breaking at either end. In either case the auxiliary safety strap 15 will hold the lineman to the pole until he is able to receive assistance.

In the modified form shown in Figure 3 50 the safety strap 10 is adjustable with respect to the auxiliary safety strap 15. Connecting members 21 encircle both straps 10 and 15, being rigidly attached to the strap 10 by means of rivets 22. These connecting members will, therefore, move with the strap 10 55 so as to allow the lineman when supported on the pole to move about with considerable ease. A stop 23 is provided on one end of the strap 15 to prevent the latter from being pulled free from connecting members 21.

In Figure 5 I have illustrated a still further modified form of my invention. In this case the strap 10 is slightly enlarged at 60 24 and slotted at 25 to allow the auxiliary strap 15 to pass therethrough. This form

also provides relative adjustment between straps 10 and the auxiliary safety strap 15.

The form shown in Figure 6 provides the auxiliary safety strap 15 in the form of two pieces 30 and 31, which may be suitably secured, as by stitching or riveting, to strap 10. While I have not shown the auxiliary safety device as being adjustable with respect to the safety strap 10, in this form, yet it may be so provided if desired. The advantage to be obtained, however, in this arrangement is lightness and economy, as the device 15 is not extended the entire distance about the looped portion of strap 10.

In Fig. 7 the auxiliary safety strap 15 encircles the post 14, while the safety strap 10 is formed in two pieces and suitably secured to strap 15 at 35, as by stitching or riveting.

In the various forms disclosed herein, the safety device 15 will function to hold the 85 lineman against falling, should the snaps 11 or buckles 6 fail, or should one end of strap 10 break.

Various modifications of the structure as herein shown may be made without departing from the spirit and scope of my invention.

I claim:

1. An article of the class described comprising a body belt, a safety strap adapted 95 for attachment to said body belt and for loosely encircling a post or the like, and an auxiliary safety device attached to and carried by said safety strap for securing the latter to and against slipping along said 100 post.

2. An article of the class described comprising a strap adapted to encircle a post to support an object when the weight thereof is placed on the strap whereby to binding- 105 ly engage the strap against the post, and an auxiliary safety strap secured to said first strap for securing the latter to the post whereby to prevent accidental slipping therealong when the weight of the object is 110 released from said first strap.

3. An article of the class described comprising a strap for holding an object to a post when suspended outwardly therefrom, and an auxiliary device attached to said 115 strap for securing said strap to the post, whereby to prevent accidental slipping therealong, when the weight of the object is released from said strap.

4. An article of the class described comprising a strap detachably connected to the body of a person for holding the latter suspended from a post or the like, and an auxiliary safety device attached to said strap for securing said strap to the post, said 125 device being so attached to said strap as to permit relative adjustment therebetween.

In witness whereof, I have hereunto subscribed my name.

CHARLES F. JACOBS.
